ELECTRICAL CONNECTER

Filed June 17, 1922.

UNITED STATES PATENT OFFICE

PAUL F. WILLIAMS, OF CHICAGO, ILLINOIS

ELECTRICAL CONNECTER

Application filed June 17, 1922. Serial No. 589,055.

My invention relates to electrical connectors, particularly of the type commonly known as potheads.

One of the objects of the invention is to provide a simple, practical and advantageous construction of device of the class specified.

Another object of the invention is to simplify and improve the connecting devices for connecting the electrical conductors, particularly in a pothead device in which there are three tubular insulating members arranged in tandem fashion, the middle one of which is moved relatively to the other two in order to secure together and separate said connecting devices.

Other objects of the invention are to improve such type of pothead construction generally.

In the accompanying drawings Fig. 1 is a longitudinal section of a pothead device of the aforesaid variety embodying my present invention;

Figs. 2, 3 and 4 are cross sections taken respectively on lines 2-2, 3-3 and 4-4 in Fig. 1.

Referring to the drawings, I show a pothead device having a lower tubular member 1, an intermediate cap-like tubular member 2 and an upper cap member 3, all of said members being preferably made of insulating material such as porcelain.

The lower member 1 is to receive a cable to be connected. Neither the cable itself nor the lower part of the member 1 is shown, as the same are well known constructions. The conductor of the cable is shown however, being indicated at 4 and being extended up to nearly the upper end of the member 1 and inserted into the recess in a socket contact member 5 which is arranged at the upper end of member 1. The other member to be connected is indicated at 6 and extends to the cap member 3, where its conductor 7 is inserted in the socket or recess in a contact member 8 carried by said cap member 3. The intermediate member 2 contains a third contact member 9 which serves as a connection between members 5 and 8, as will be more fully explained.

50 The member 5 is held in position in the

upper part of member 1 by means of a metal collar 10 which is provided with a flange 11 having an aperture adapted to permit collar 10 to pass freely over the threaded exterior of extension 5^a. The collar 10 is secured to member 1 by a layer 13 of cement, said member 1 preferably having an annular recess 14, in the lower portion of which said cement 13 is located. Threaded washers 15 and 16 are arranged on extension 5^a, and serve as lock nuts therefor. Rotary movement of member 5 relatively to collar 10 is limited by projections 10^a on collar 10 and projections 5^d on member 5 (Fig. 4).

Member 5^a has a threaded socket into which the reduced threaded end 9^a of member 9 may be screwed. This threaded end 9^a may be adjusted in the threaded socket of extension 5^a by turning it relatively to the latter, which turning movement may be accomplished by means of the intermediate member 2. To this end member 9 is provided with outwardly projecting ears or lugs 17 (Figs. 1 and 2) and member 2 with recesses 18, into which lugs or wings 17 may fit, so that member 2 will act on wings or projections 17 and rotate member 9. Rotation of member 9 by member 2 will screw extension 9^a into threaded socket of extension 5^a, and downwardly to such an extent that bottom of extension 9^a will strike against bottom on threaded socket of extension 5^a, and thus form a good mechanical joint and good electrical contact, member 5 being held to permit such in-screwing of member 9^a by projections 5^d and 10^a.

Member 9 has its upper end provided with a threaded socket 20, into which fits a threaded plug member 21 secured to and preferably formed integrally with the contact member 8 carried by cap 3. Upper end of member 21 is preferably made square at 21^a to prevent turning in cap 3. Threaded washers 22 and 23 are fitted over threaded member 21 and hold the same and terminal 8 firmly in position in cap member 3. The threads of members 21 and 9^a are of different kind, that is one, as 21, is left handed and the other, as 9^a, is right handed. Hence the rotation of the member 9 by member 2 in one direction will screw member 9^a down in threaded

socket 5^b and will also screw member 9 upwardly on member 21, thereby in effect screwing member 21 down in socket 20, as a result of which turning movement in this one direction will screw both members 9^a and 21 into their threaded sockets, and thereby make firm mechanical and good electrical contact. Conversely, rotation of member 2 in the opposite direction will in effect screw members 9^a and 21 out of their threaded sockets.

Thus it will be seen that connection may be made by first cementing collar 10 in position in member 1 and then passing member 5^a up through it, cable conductor 4 having previously been secured in socket member 5 as by soldering. Washers 15 and 16 are then fitted over 5^a to hold same in position. Member 2 is then mounted on member 1 and threaded end 9^a screwed into socket 5^b. Conductor 7 of wire 6 is secured to terminal 8, as by soldering, and then plug member 21 is screwed into socket 20. Intermediate insulating member 2 is then rotated so as to turn member 9 and thereby in effect screw threaded members 21 and 9^a into their respective sockets. This will make a firm mechanical connection and a tight electrical contact.

The member 21 is provided with a threaded socket into which a member 25 is screwed and this member 25 extends also into a central bore formed in member 9^a. This member 25 is tubular and contains a pin 26 which has its lower end threaded and screwed into member 5. The member 25 is preferably slotted as at 27. By this arrangement there are provided removable spark contacts 25 and 26 between which the spark takes place in case there is a spark when the circuit is opened by the separation of contact members 9^a and 5^a. By making these spark contacts removable, they can be readily replaced when worn or torn by sparks and by making them separate from the main contacts 9^a and 5^a, they may be replaced at very little expense. The sparking will obviously take place between the lower end of member 25 and the upper end or head of member 26 when those members are about opposite and separating from one another, at which time the members 9^a and 5^a are also separating from one another. To replace the members 25 and 26 or either one of them when they become worn or used, either one or both are screwed out of their respective sockets and others substituted.

It will be understood that changes and modifications may be made without departing from the spirit of the invention.

What I claim is:

1. The combination of end and intermediate members whereof the end members are provided with conductor terminals and the intermediate member with a connecting member for connecting said terminals, and means for taking up a spark at break, said means

comprising members detachably mounted on said terminals.

2. The combination of end and intermediate members whereof the end members are provided with conductor terminals and the intermediate member with a connecting member for connecting said terminals, and means for taking up a spark at break, said means comprising members detachably mounted on said terminals, one of said members having screw threaded connection with one of said terminals and the other having threaded connection with the other terminal.

3. The combination of end and intermediate members whereof the end members are provided with conductor terminals and the intermediate member with a connecting member for connecting said terminals, and means for taking up a spark at break, said means comprising members detachably mounted on said terminals, one of said members being tubular and the other being a pin adapted to fit into said tubular member.

4. The combination of end and intermediate members whereof the end members are provided with conductor terminals and the intermediate member with a connecting member for connecting said terminals, and means for taking up a spark at break, said means comprising members detachably mounted on said terminals, one of said members being tubular and the other being a pin adapted to fit into said tubular member, said tubular members having a threaded connection with one terminal and passing through the connecting member and the other of said members having a threaded connection with the other terminal and fitting into a recess in the first mentioned member.

5. A device of the class specified comprising end and intermediate outer members, contact terminals for the conductors arranged within and carried by the end members and a connecting device for connecting said terminals, said connecting device being connected with the intermediate member for operation thereby, and said connecting device and terminals having means for making end contact with one another, said terminals and connecting device having screw threaded connection with one another and being provided with transverse abutments against which the same may be secured to make said end contacts, one of the terminals having a threaded plug portion and the other having a threaded socket portion and the connecting device having a threaded socket to receive said threaded terminal portion and having a bottom against which the same may make contact, and said connecting device also having a threaded plug portion to fit into the threaded socket portion of said other terminal and also having abutments against which the end of said terminal may make contact when said connecting device and terminal are secured together.

6. The combination of an outer member, a conductor terminal therein, and an annular member within the outer member and surrounding said terminal, said annular member and said terminal being provided with cooperating projections limiting the extent of rotary movement on the part of the terminal.

7. The combination of an outer member, a conductor terminal therein, and an annular member within the outer member and surrounding said terminal, said annular member and said terminal being provided with cooperating projections limiting the extent of rotary movement on the part of the terminal, the end portion of said terminal being threaded and threaded washers engaging said threaded portion of the terminal and also engaging said annular member to hold said terminal firmly in position.

In witness whereof, I hereunto subscribe my name this 12th day of May, A. D. 1922.

PAUL F. WILLIAMS.
